UNITED STATES PATENT OFFICE

ROBERT J. BANNER, OF YOUNGSTOWN, OHIO

EDGING MILL

Application filed May 5, 1928. Serial No. 275,332.

In rolling articles of the character of those termed flats, skelp, strips, hoops, bands and the like in the steel trade it is necessary to slightly reduce the width of the articles by 5 the application of rolling action to the edges thereof for the purpose of maintaining a uniform width in the article or in order to produce a section having edges of the desired contour or for both of these purposes. This 10 operation has heretofore generally been effected by means of edging mills having vertical rolls or by vertical rolls incorporated as a part of the main rolling mill but in either case the necessary machinery is of complicated character and involves a relatively heavy expense for upkeep.

Particularly in the rolling of the material known as "grooved skelp" has great difficulty been experienced with the machines hitherto 20 employed in producing a section of uniform width having uniformly square edges or edges of a desired bevel or taper and with sharp corners. The difficulty in effecting this desired result generally arises from un- 25 even temperature of the piece being rolled but may be due to some other causes equally hard to control under practical conditions of operation and manifests itself in uneven edges and uneven or non-uniform width of 30 the rolled material, both of these conditions being produced because the grooved passes in the rolls are alternately over-filled or under-filled by the piece as it passes therethrough. In a modified degree the same 35 conditions exist when plain rolls without grooved passes are employed and with a view, under these conditions, of minimizing or altogether eliminating variations in the width of the piece as well as to produce a 40 piece having satisfactory edges, one or more edging mills are introduced between the various passes or beyond the finishing pass so as to operate on and true up the edges of the piece. With the same object in view the 45 piece when of comparatively narrow width is sometimes twisted or turned through an angle of 90° while traveling from one stand of rolls to the next in such manner that the second stand performs the work of an edging 50 mill upon the piece which is again turned

down flat before entering the next pair of horizontal rolls. This procedure, however, is open to various practical objections and in any case is limited to use with pieces of comparatively narrow width.

A principal object of my invention therefore is to provide means in the nature of an edging mill of improved and greatly simplified design which may be satisfactorily employed in the rolling of grooved skelp as well as in the rolling of other material of rectangular or any other cross section to produce an article of uniform size and width having sharp corners and uniformly square, beveled or tapered edges as the case may be.

A further object of my invention is to provide an edging mill for the performance of the aforesaid function which is of simple design, which may be rapidly adjusted for use with different widths of material or those having different sections, which is so constructed as to facilitate repairs in case of necessity and in which because of the comparatively light weight of the various parts replacements can be readily made when required at a minimum of expense with the result that the use of my invention tends to facilitate production, reduce operating costs and improve the ultimate product.

My invention further includes other objects, advantages and novel features of design, construction and arrangement hereinafter more particularly described or which will be apparent from the accompanying drawings in which I have illustrated a preferred embodiment of the invention to which reference will now be made.

In the said drawings Fig. 1 is a top plan view of an edging mill embodying the principles of my invention, a piece of skelp being shown in the act of passing through the mill; Fig. 2 is a somewhat fragmentary front view of the mill shown in Fig. 1 and Fig. 3 is a fragmentary end view thereof. The same numerals are used to designate the same parts in the different figures.

The particular embodiment of the invention which I have chosen to illustrate comprises a base adapted to be secured to the runout table of preceding stand of horizontal rolls in any

suitable way; as the particular shape of this base will necessarily vary in conformity with the construction of the runout table or other part to which it is to be attached, it will be understood that the supports X conventional-
ly indicate suitable portions of the runout table or other portion of the preceding stand of rolls to which the base of the edging mill is arranged to conform and to which it is suitably secured. The base of the mill com-
10 prises laterally spaced side members 1, 2 while above the latter housings 5, 6 extend respectively upward and are rigidly bolted to the side members at their lower extremities; these housings are preferably tied together transversely by rails 7, 8.

Within the side members and housings is suitably journaled the lower horizontally ex-
15 tends pinch roll shaft 10 carrying at its center the lower pinch roll 11 while the upper pinch roll shaft 12 carrying the upper pinch roll 13 is journaled in the housings 5, 6; these shafts are vertically spaced one above the other and have their respective pinch rolls disposed in vertical alignment. Desirably the lower shaft 10 is disposed with its axis substantially on the plane of separation be-
20 tween the upper housings and side members and in such manner that by taking off the housings 5, 6 it may be readily removed from the mill, while to facilitate removal of the upper pinch roll shaft which is journaled in vertically slideable boxes 14 disposed in slots in the upper housings, the latter are provided
25 with removable caps 15, 16 which can be readily taken off to permit the boxes to be lifted out vertically with the shaft. Springs 20 disposed in the slots above the boxes and beneath the caps may be compressed to any desired extent by adjusting screws 21 whereby the pressure of the upper pinch roll on the work passing through the mill may be adjusted to any desired degree.

For driving the lower pinch roll, the lower
30 pinch roll shaft 10 is provided with a bevel gear 22 on one of its ends adapted to mesh with a corresponding gear on the runout table line shaft (not shown), this being a convenient source from which to derive the necessary power but any other suitable source may be utilized if desired. In the particular embodiment of the invention illus-
35 trated, no driving mechanism is shown for the upper pinch roll shaft but it is ob-
40 vious to those familiar with the art that the same may be provided if desired and may be of any suitable form adapted to drive the upper shaft at the same rate as the lower while, under some conditions, it may be pre-
45 ferred to drive the upper shaft alone without driving the lower one.

For effecting the requisite work on the lateral edges of the piece of skelp or other material M as it passes through the mill, two
50 edging rolls 25, 26 are disposed in laterally

spaced relation on opposite sides of the pinch rolls and respectively arranged to rotate on axes preferably but not necessarily normal to the axes of the pinch rolls in the same plane or in a plane parallel to that in which the latter are disposed. These rolls are similarly mounted, each being carried in a yoke-like frame 27 provided with a slot for the reception of the roll which is arranged to revolve on a suitable pivot 28 carried by the frame; if desired the roll may be provided with an anti-friction bearing of any suitable type. One end of each of the frames 27 is pivoted on a suitable pivot 29 between the rail 7 and a projecting arm 30 extending inwardly from the adjacent hous-
70 ing so it can swing about the pivot horizontally while its opposite end overlies the opposite rail 8 and is adapted to be secured thereto by a clamping bolt 32 carrying a nut 33 at its lower extremity and extending downwardly through a slot 34 in the yoke and a corresponding slot 35 registering therewith and formed in the rail whereby the yoke may be rigidly secured to the rail in any position of angular adjustment to which it may be moved about the pivot 29.

To facilitate exact adjustment of the positions of the yokes and in turn of the edging rolls which they carry, adjusting screws 36 carrying lock nuts 37 are extended through the housings respectively adjacent the yokes so as to bear on the outer faces thereof as best shown in Fig. 1 so that when the clamping bolts 32 are loosened the yokes may be moved inwardly by setting up on the adjusting screws or moved outwardly by hand after the latter are backed off. Since during the operation of the mill the thrust of the work piece on the edging rolls is exerted outwardly in opposite directions, the adjusting screws 36 are thus, in large measure, effective to resist and support this thrust thereby correspondingly relieving the clamping bolts 32 with the result that after the desired adjustment of the edging rolls is effected it is unnecessary in order to preserve such adjustment to set up the clamping bolts as tightly as might otherwise be required in the absence of adjusting screws.

Prior to the operation of the mill it is necessary to select and install therein a pair of pinch rolls of a width suitable for use with the particular width of skelp or other material which is to be rolled, but it will be observed that it is unnecessary to preserve any exact relation between the width of the pinch rolls and the width of the skelp other than to have the former somewhat narrower than the latter so as to leave the edges of the work piece clear for the operation of the edging rolls. It is also necessary to install in the mill edging rolls whose profiles or faces are suitable for the edge work to be performed on the material which is to be

rolled; thus, for example, when the latter is to be of rectangular section, edging rolls having their faces parallel with their axes (as shown) will be employed, but where the edges of the skelp are to be beveled, grooved or the like edging rolls having correspondingly formed faces will be utilized. The proper rolls having been suitably installed in the mill, the edging rolls are then adjusted 5 by means of the adjusting screws so as to provide a pass of proper width and then clamped in position by the clamping bolts, and the springs 20 are also adjusted by means of adjusting screws 21 to exert sufficient pressure on the skelp to insure its being fed through the mill by the pinch rolls, thus putting the mill into condition for operation. During the latter, the function of the pinch rolls is threefold; first, to insure the passage 10 of the work through the machine particularly after the rear end of the work has cleared the preceding stand of rolls for as the edging rolls are undriven and thus incapable in themselves of moving the work along, the moment the latter clears the preceding stand 15 its further progress would be arrested were it not for the thrust exerted on it by the pinch rolls. The second function of the pinch rolls is to assist in advancing the work 20 through the machine when the latter is located so far from the preceding stand of rolls that the thrust of the latter tends to buckle the work lengthwise as it encounters the resistance offered by the edging rolls. 25 The third and perhaps most important function of the pinch rolls, however, is to prevent the work from arching transversely on itself under the action of the edging rolls as it is obvious that this arching, should it occur, 30 would prevent the production of straight and uniform edges on the work. Extending as they do across the major portion of the work and contacting with the upper and lower faces thereof substantially coincident with 35 the line or zone in which the thrust of the edging rolls is delivered to the lateral edges of the work, the pinch rolls thus serve to effectually prevent the arching of the work and consequently insure the desired uniformity and straightness of the edges thereof. 40 Thus for the most satisfactory conditions of operation, the pinch rolls should be of a width approaching that of the work and adjusted to exert sufficient pressure 45 thereon to prevent any arching or transverse bending thereof, and further, of course, when the upper and lower surfaces of the latter are not flat, the faces of the rolls should be grooved, arched or otherwise formed so 50 as to conform thereto.

It will thus be apparent that an edging mill embodying the principles of my invention when operated in conjunction with a rolling mill or the like is substantially automatic in action and requires no attention 55

on the part of the operator after it is once adjusted for a particular kind and size of work. Moreover, by reason of its simple and rugged construction it is not liable to get out of order or become damaged under 60 the severe conditions of operation to which machines of this character are necessarily subjected, while the adjustments necessary to adapt the mill to different classes of work including the substitution of different sizes 65 and forms of pinch and edging rolls as may be required may be readily effected when required.

While I have herein described and illustrated a preferred form of my invention with considerable particularity, I do not thereby desire or intend to confine myself to any precise details of design, construction and arrangement of the different parts as various modifications and changes may be made 70 therein to adapt the machine for operation under various conditions or for other purposes as may be desired, without departing from the spirit and scope of the invention as defined in the appended claims.

Having thus described my invention, I claim and desire to protect by Letters Patent of the United States:

1. In a mill of the class described, the combination of a pair of vertically spaced pinch rolls rotatable on horizontal axes, means for driving at least one of said rolls, means for adjusting the pressure exerted by the rolls on a work piece disposed between them, a pair of edging rolls rotatable on vertical axes and substantially horizontally aligned with the plane of separation between the pinch rolls and laterally spaced on opposite sides thereof respectively, a frame arranged to support each edging roll substantially midway between the ends of the frame, means for supporting each end of the frame, and means for adjusting the position of the frames to vary the distance between the edging rolls.

2. The combination of a pair of vertically spaced pinch rolls rotatable on horizontal axes, means for driving at least one of said rolls, means for adjusting the pressure exerted by said rolls on a work piece disposed between them, a pair of edging rolls freely rotatable on vertical axes and disposed substantially midway between the axes of rotation of the pinch rolls and laterally spaced on opposite sides thereof respectively, a pivoted frame supporting each edging roll and movable at one end about a vertical pivot, means for moving each frame about its pivot to effect adjustment of the distance between the edging rolls, and means for clamping the other ends of the frames in adjusted position.

3. In a mill of the class described, the combination of a pair of laterally spaced housings, a pair of vertically spaced pinch rolls disposed therebetween, rotatable on parallel axes and adapted to engage opposite faces of

a work piece passing between them, means for maintaining said housings in rigid alignment comprising a slotted rail and another rail substantially parallel thereto, frames respectively pivoted to the last mentioned rail and adapted to be adjustably secured to said slotted rail, a pair of edging rolls carried by said frames rotatable respectively on axes substantially coincident with the plane of the axes of the pinch rolls and adapted to engage other faces of the work piece, and adjustable means carried by the housings adapted to resist outward lateral displacement of said pivoted frames.

4. In a mill of the class described, a pair of laterally spaced housings, a pair of longitudinally spaced rails supported thereby, a pair of vertically spaced rotatable pinch rolls adapted to engage opposite faces of a work piece disposed between them, a pair of frames respectively pivotally supported by one of said rails and adapted to be adjustably secured to the other rail, and an edging roll supported by each frame between said rails adapted to engage the work piece as it passes between the pinch rolls and rotatable on an axis lying substantially in the plane of the axes thereof.

5. In a mill of the class described, a pair of laterally spaced edging rolls, means for supporting said edging rolls comprising a pair of frames, means for supporting said frames comprising a pair of rails longitudinally spaced on opposite sides of said rolls, one end of each frame being pivotally supported by one of said rails and the opposite ends of said frames being adjustably supported by the other rail, means adapted to operatively clamp said frames to said last mentioned rail, means operative to assist in retaining said frames in a predetermined lateral relationship, and a pair of pinch rolls rotatable on axes perpendicular to the axes of the edging rolls and in a plane substantially coincident therewith adapted to engage a work piece and through rotation to effect the passage thereof between them and between the edging rolls.

6. In a mill of the class described, a pair of horizontal pinch rolls, housings disposed upon opposite sides of the rolls and forming journals therefor, said housing being respectively vertically separable substantially in the plane of the axis of the lower roll to permit removal thereof and also comprising means to permit removal of the upper roll whereby said rolls may be readily interchanged when required, a pair of transversely extending horizontal rails disposed on opposite sides of said rolls, a pair of frames respectively disposed adjacent the opposite ends of said rolls, an edging roll rotatably mounted adjacent the center of each frame, means for pivotally securing one end of each frame to the adjacent rail, adjustable means for

operatively securing the other end of each frame to the other rail, and means for adjustably limiting the outward pivotal movement of each frame.

In witness whereof, I have hereunto set my hand this 30th day of March, 1928.

ROBERT J. BANNER.
